UNITED STATES PATENT OFFICE.

WILMER M. NEAR, OF SHELBY, MICHIGAN.

SPARK-PLUG TESTER.

1,245,368.

Specification of Letters Patent.

Patented Nov. 6, 1917.

Application filed April 14, 1917. Serial No. 162,128.

To all whom it may concern:

Be it known that I, WILMER M. NEAR, a citizen of the United States, residing at Shelby, in the county of Oceana and State 5 of Michigan, have invented certain new and useful Improvements in Spark-Plug Testers, of which the following is a specification, reference being had to the accompanying drawings.

10 This invention comprehends certain new and useful improvements in spark plug testing devices, and it has for its primary object a practical, durable, efficient and compact article of this character which may be very 15 easily carried in one's pocket or occupy very little space in a tool box or kit, whereby it will be always at hand and capable of being quickly applied to the spark plug or plugs to be tested, and without the necessity 20 of disconnecting the same.

A further object of the invention is an improved spark plug tester embodying a relatively stationary electrode and a relatively movable or adjustable electrode with 25 simple and efficient means whereby the last named electrode may be adjusted to increase or decrease the gap across the adjoining points or ends of the two electrodes, so as to determine the proper gap for the spark 30 plug being tested at which the hottest and otherwise best spark will be produced thereby.

And the invention also aims to generally improve devices of this class so as to render 35 them more useful and commercially desirable.

With these and other objects in view, as will more fully appear as the description proceeds, the invention consists in certain 40 constructions, arrangements and combinations of the different parts that I shall hereinafter more fully describe and claim.

For a full understanding of the invention, reference is to be had to the following description and accompanying drawing, in which—

Figure 1 is a side elevation of a spark plug tester embodying the improvements of my invention, parts being shown in section.

50 Fig. 2 is a transverse longitudinal section on the line 2—2 of Fig. 1.

Figs. 3 and 4 are detail perspective views of the contact members.

Fig. 5 is a detail view of a finger nut 55 employed and hereinafter specifically referred to, and

Fig. 6 is a side view showing the device in applied position.

Corresponding and like parts are referred to in the following description and accompanying drawing by like reference characters.

Referring to the drawing, the numeral 1 designates a block which may be formed of any desired or suitable insulating substance or material, said block being substantially oblong in form, except that it is formed in one longer side with a preferably angular recess 2 which in the present instance embodies two inwardly extending obliquely disposed surfaces 3 and 4. Secured to the surface 3 by means of screws or similar fastening devices is a metallic contact member 5, and secured similarly to the surface 4 is a complementary metallic contact member 6, 75 these two members being designed respectively for engagement with the top screw at the top of the spark plug to be tested and the base of the plug.

The block 1 is formed with two longitudinally aligned bores designated 7 and 8 respectively and intersected by a preferably circular opening 9 which extends from one side face of the block to the other. The relatively stationary electrode 10 in the form of 80 a metallic rod, as shown, is mounted in the bore 8 and preferably provided at its outer end with a head 11, the contact member 6 being provided with an angularly disposed extension 12 which extends over one end of 85 the block 1 and over and into contact with said head. And the inner end of said electrode extends into the opening 9 where the gap is formed for the spark to jump across.

13 designates the relatively movable or 90 adjustable electrode of the device, and this is received within the bore 7 hereinbefore mentioned, said electrode 13 being also composed of a metallic rod formed intermediate 95 of its ends with screw threads 14 for engagement by a preferably knurled nut 15 of fiber or the like provided with a centrally disposed washer 16 for direct engagement with the threads 14. This finger nut 15 is mounted within a transversely extending opening 100 1' formed in the block 1 and the electrode 13 is formed at its outer end with one or more wings or vanes 17 as shown designed 105 for engagement in grooves formed in the wall or bore 17, whereby, as is manifest, 110 when the finger nut 15 is turned the electrode 13 will be moved toward or away from the

electrode 10, so as to decrease or increase the gap.

The contact member 5 is formed at one end with a lateral extension 19, having an angularly disposed extremity 18, the same being designed to extend into an opening 20 formed in the block in the inclined surface 3 thereof, said opening 20 communicating with the bore 7 and the extremity 18 bearing 10 resiliently against the electrode 13 so as to provide the required electrical connection.

From the foregoing description in connection with the accompanying drawing, the operation of my improved spark plug tester 15 will be apparent. In the practical use of my device, the contact member 6 is placed against the base of the spark plug to be tested, and the contact member 5 against the top of the plug, whereupon as is manifested, if the plug is working, the spark will jump across the gap between the adjacent ends of the electrodes 10 and 13. By adjusting the electrode 13 through the instrumentality of the finger nut 15, it is obvious 25 that the approximate actual distance apart of the spark plug points may be determined, and by the experiments made with the device the points may be adjusted properly so as to secure the best results.

It will thus be seen that I have provided 30 a very practical, durable and efficient construction of spark plug tester, the parts of which may be easily manufactured and readily assembled, and not liable to get out of 35 order.

While the accompanying drawing illustrates what I believe to be the preferred embodiment of my invention, it is to be understood that the invention is not limited thereto, but that various changes may be made in 40 the construction, arrangements and proportions of the parts without departing from the scope of the invention as claimed.

What is claimed, is:

1. A spark plug tester, comprising a block formed intermediate of its ends with a transversely extending opening, electrodes carried by said block in longitudinal alinement with each other and having their adjoining ends 50 extending into said opening, and contact members secured to one face of said block, one of said contact members engaging with one of the electrodes and the other contact member being formed with a lateral extension 55 projecting into the block and having its extremity resiliently engaging the other electrode.

2. A spark plug tester of the character described, comprising a block formed inter-

mediate of its ends with a transversely extending opening, electrodes carried by the block in longitudinal alinement with each other and having their adjoining ends extending into said opening, contact members secured to one face of the block, one of said contact members having a lateral extension projecting into the block into engagement with one of the electrodes and the other contact member being formed with an angularly disposed extension extending over the 60 end of the block and over and in contact with the outer end of the other electrode.

3. A spark plug tester of the character described, comprising a block having two bores formed therein in longitudinal alinement 65 with each other, and an opening separating said bores, a relatively stationary electrode mounted in one of said bores and extending into said opening, an electrode mounted in the other bore and formed intermediate of 70 its ends with screw threads, a nut mounted in said block and engageable with the threads of said second named electrode, and contact members secured to the block and 75 engaging the electrodes respectively.

4. A spark plug tester of the character described comprising a block formed in one edge with two inclined surfaces, contact members secured to said surfaces, the block being formed with longitudinal bores in 80 alinement with each other, and a transversely extending opening separating said bores, a relatively stationary electrode mounted in one of said bores, one of said contact members being formed with a lateral extension engaging the outer end of said electrode, another electrode mounted in the other bore and formed intermediate of its 85 ends with screw threads and at one end with a wing engaging the wall of said bore, the block being formed with a transverse opening intersecting said bore, a finger nut mounted in said last named opening and 90 engaging the threads of the second named electrode, the block being further formed in 95 one of said inclined surfaces with an opening communicating with the bore in which the threaded electrode is mounted and the other contact member being formed with a lateral extension received in said last named 100 opening and having an angular extremity 105 engaging said threaded electrode.

In testimony whereof I hereunto affix my signature in the presence of two witnesses.

WILMER M. NEAR.
